CLAIM

The ornamental design for a tub as shown and described.

DESCRIPTION

FIG. 1 is a perspective view of a tub of the new design; FIG. 2 is a side elevational view of the tub of FIG. 1, the other side elevational view being a mirror image thereof; FIG. 3 is an end elevational view of the tub of FIG. 1; FIG. 4 is a top plan view of the tub of FIG. 1; FIG. 5 is a cross-sectional view of the tub of FIG. 1, taken along the line 5-5 in FIG. 4, showing the contour of a portion of the exterior surface of the tub; FIG. 6 is a detailed view of a circled portion of FIG. 5; FIG. 7 is a cross-sectional view of the tub of FIG. 1, taken along the line 7-7 in FIG. 4, showing the contour of another portion of the exterior surface of the tub; FIG. 8 is a detailed view of a circled portion of FIG. 7; FIG. 9 is a cross-sectional view of the tub of FIG. 1, taken along the line 9-9 in FIG. 4, showing the contour of another portion of the exterior surface of the tub; and, FIG. 10 is a detailed view of a circled portion of FIG. 9. The broken lines in the drawings show portions of the tub that form no part of the claimed design. The dot-dot-dash broken lines shown in FIGS. 5-10 define the boundary of the enlargement area and form no part of the claimed design.

1 Claim, 5 Drawing Sheets
